UNITED STATES PATENT OFFICE

2,051,880

APPARATUS FOR HEATING FLUIDS

Lev A. Mekler, Chicago, Ill., assignor, by mesne assignments, to Universal Oil Products Company, Chicago, Ill., a corporation of Delaware

Application November 22, 1936, Serial No. 497,556
Renewed November 6, 1935

5 Claims. (Cl. 122—356)

This invention relates to improvements in furnaces for heating fluids, and refers particularly to a means for controlling the rate of heat input into various portions of the heating element and increasing the effective heating surfaces of said element.

This invention is particularly applicable to furnaces such as those employed in heating oils in which radiant and/or convection heating surfaces are employed. In such a furnace the invention provides a method and means for controlling the rate of heating in various portions of either the convection or the radiant heat banks, or both, making it possible to obtain any desired heating curve for the oil undergoing treatment and at the same time providing a means for increasing the effective heating surface in the radiant heat bank.

Other and further objects and advantages of my invention will be apparent from the accompanying drawing and following detail description.

In the drawing, Fig. 1 is a cross-sectional view of a furnace provided with apparatus suitable for carrying out my invention.

Fig. 2 is a sectional plan view taken on a line 2—2 of Fig. 1.

Referring in detail to the drawing, reference being made particularly to Fig. 1, 1 indicates a furnace having a roof 2, rear wall 3 and front or firing wall 4, said roof and walls forming an enclosure for combustion chamber 5. A baffle wall 6 may be disposed within combustion chamber 5 adjacent rear wall 3 providing a space 7 between said rear wall and the baffle 6. A flue 8 may connect the lower portion of the space 7 to a suitable stack (not shown). If desired, a plurality of fluid passageways or tubes 9 may be positioned within the space 7 and may be adapted to be heated by convection or sensible heat from combustion chamber 5.

A combustion block 10 may be positioned in the lower front portion of the furnace 1 and may be provided with central combustion tunnel 11 and auxiliary tunnels 12 and 13, which latter tunnels may be provided with suitable dampers 14 and 15, respectively. Fuel may be introduced into central tunnel 11 by means of burner 16, said fuel being conducted to said burner from a suitable source of fuel supply (not shown) by means of pipe 17. It is to be understood that gas, oil, pulverized coal, or any other fuel may be burned, but preferably the fuel must be burned under such conditions that

a high degree of radiant heat is given off into combustion chamber 5.

A baffle 18 may be disposed within combustion chamber 5 and a plurality of fluid passageways or tubes 19 may be positioned in the space 20 between the baffle 18 and the front wall 4.

A plurality of tubes 21 may be positioned in one or more rows adjacent the roof 2 of the furnace and, as a feature of my invention, I may dispose a substantially semi-cylindrical or trough-like protector 22 adjacent the lower surfaces of each of said tubes and spaced from said tubes by suitable arms or spacers 23. Spaces 24 may be provided between adjacent tubes 21 through which gases of combustion from combustion chamber 5 may pass, and in order to control the quantity of said gases which pass adjacent the tubes 21 with respect to the position of each of the tubes in the row or rows I may provide a plurality of baffle plates 25 between said adjacent tubes. It can readily be seen that the draft which may tend to draw the combustion gas from the combustion chamber 5 to the space 7, the flue 8 and the stack will be greater in the vicinity of those tubes located adjacent baffle wall 6 and will progressively diminish in intensity along the row of tubes 21 toward the front end of the combustion chamber. To compensate for this inequality in draft along the row of tubes 21 I may provide a relatively greater number of baffle plates 25 adjacent those tubes near the wall 6 than those tubes adjacent wall 4. In this manner substantially the same quantity of hot combustion gases will come into contact with all the tubes which constitute the row.

In heating fluids the same are usually confined within a cylindrical or substantially cylindrical zone such as a tube or shell, and when said cylindrical zone is exposed to radiant heat the area of the surface of said tube or shell exposed to the radiant heat will be substantially equal to the projected area of said tube or shell upon a plane parallel to the plane of the source of heat. In other words, the effective area of the tube will be equal to the product of its length by its diameter, which as can readily be seen comprises only about one-third of the total area of the tube. In other words, where a tube is exposed to radiant heat the greatest portion of heat transferred to the tube takes place over about one-third the surface of the tube. Whereas, a relatively smaller portion of the heat transfer takes place over the remaining two-thirds of the tube.

To uniformly distribute the heat about the entire area of the surface of the tube is an object of my invention. I accomplish this object by surrounding that portion of each of the tubes exposed to radiant heat with the shields or protectors 22 which serve virtually as a secondary source of radiant heat distributed substantially uniformly around the lower portion of the tubes comprising about one-half their surface. In addition, due to the spacing of the troughs or protectors 22 from the tube surface the lower portion of said tube will not absorb as much radiant heat as if it were unprotected, and hence a greater quantity of residual heat unabsorbed by the lower one-half of the surface of the tubes will pass between adjacent tubes, or more strictly speaking between adjacent protectors in the spaces 24, and will be available for heating the upper portion of the tube surfaces by radiation and convection from the gases as well as re-radiation from the heated roof of the furnace. In this manner the quantity of heat absorbed by the lower half portion of each of the tubes will be relatively diminished and will be more evenly distributed over said lower half portion, and the quantity of heat absorbed by the upper half portion of said tubes will be relatively increased, thereby subjecting substantially the entire surface of each of the tubes to a more uniform quantity of radiant heat.

If desired, the character of the products of combustion introduced into the combustion chamber 5 through the central combustion tunnel 11 may be altered or controlled in the combustion zone of the furnace to give different degrees of flame luminosity and flame temperature by varying the proportion of secondary air and primary air. This may be accomplished by introducing greater or smaller quantities of secondary air and/or by altering the products of combustion by the introduction of excess air or inert gas through either or both of the tunnels 12 and 13. The radiant properties of the products of combustion may also be increased by the introduction of steam or carbon dioxide through either or both of tunnels 12 and 13.

In addition, a thermo-siphon may be effected within the combustion chamber 5 of the furnace, the combustion gases therein taking the path indicated by the arrows 26. The hot combustion gases discharged from tunnel 11 along the floor into combustion chamber 5 may be directed to wall 6 so that the floor and the wall 6 become relatively hot. Said gases may pass upwardly along said wall and may come in contact with the relatively cool surfaces of the protectors or shields 22. Said gases by this contact become cooled and will pass downwardly through space 20 and adjacent tubes 19 and will again come in contact at the lower end of said space with the hot combustion gases freshly introduced into combustion chamber 5 from the tunnel 11.

It has been found that, for example, in the heating of hydrocarbon oils to conversion temperatures the use of tube shields such as herein provided permit higher furnace temperatures than are otherwise practicable without local overheating and excessive decomposition of the oil. With the same total heating surface the higher initial furnace gas temperatures also permit higher total heat absorption.

As a specific example of the increased efficiency of a heating element employing shields such as provided by the present invention over 75 the same furnaces operated without the use of

the shields the effectiveness of the heating element as manifest by increased capacity or throughput was increased some 15 percent when shields were used in the first two rows of the convection heat bank.

I claim as my invention:

1. In combination, a furnace, a combustion chamber and a convection chamber within said furnace, a plurality of spacedly disposed heating tubes within said combustion chamber, metallic shields associated with and spacedly disposed from said tubes to afford a source of radiant heat for the lower portion of the same, a reradiating surface adjacent the upper portion of said tubes, spaces between said metallic shields through which combustion gases may pass to said reradiating surface, means associated with said metallic shields to control the quantity of combustion gases passing to said reradiating surface, and means for passing combustion gases after passage through said shields and over said reradiating surface to said convection chamber.

2. In combination, a furnace, a combustion chamber and a convection chamber within said furnace, a plurality of spacedly disposed heating tubes mounted within said combustion chamber, metallic shields spacedly disposed from and surrounding the lower portions of said tubes and affording a source of radiant heat for the same, a reradiating surface disposed above said tubes affording a source of heat for their upper portions, communications between said metallic shields for passing combustion gases from said combustion chamber between said shields and onto said reradiating surface, further means for controlling the amount of combustion gases passing between said shields so as to effect a uniform heating of the tubes within said combustion chamber, and means for passing spent combustion gases from said combustion chamber onto a plurality of heating tubes disposed within said convection chamber.

3. In combination, a furnace, a combustion chamber within said furnace, a plurality of fluid conduits within said combustion chamber, a plurality of concentric shields associated with said conduits and adapted to provide a source of radiant heat therefor, a re-radiating surface oppositely disposed from said concentric shields and said conduits, means for supplying heat to said combustion chamber and shields, and means interposed between said shields for uniformly distributing heating gases over said shields and said re-radiating surface.

4. In combination, a furnace having a heat radiant wall and a source of heat, heating tubes between said wall and the heat source and arranged to receive radiant heat on one side thereof from the wall, and a heat radiant shield surrounding and spaced from the opposite side of each of the tubes, the shields being spaced from each other to permit direct transmission of heat from the heat source to said wall.

5. In a furnace having a heat radiant roof and heating means adjacent the lower portion thereof, the combination of a horizontal row of heating tubes adjacent the roof, the upper sides of the tubes being exposed to the radiant heat of the roof, and a heat radiant shield surrounding and spaced from the lower side of each of the tubes, the shields being spaced from each other to permit direct transmission of heat from the heating means to the roof.
